UNITED STATES PATENT OFFICE

FRIEDRICH TOTZER, OF ESSEN-STOPPENBERG, GERMANY, ASSIGNOR, BY MESNE ASSIGNMENTS, TO THE KOPPERS COMPANY OF DELAWARE, OF PITTSBURGH, PENNSYLVANIA, A CORPORATION OF DELAWARE

COKE OVEN

Application filed December 12, 1928, Serial No. 325,615, and in Germany December 12, 1927.

My invention refers to the production of gas and coke from coal and more especially to a coking retort oven of the regenerative type, in which the regenerators extend in the longitudinal direction of the battery of juxtaposed ovens.

It is an object of my invention to improve this type of oven by providing same with a connection between the regenerators and the heating flues by means of canals extending horizontally above the regenerators and below the heating flues, as described with reference to coke ovens of the cross-regenerative type in my copending application for patent for "retort oven for producing gas and coke". By this arrangement of horizontal connections the length of the paths of the heating media for the heating flues combined in a heating wall is rendered uniform to the extent of rendering the throttling of the cross-sectional areas of inlet of the single flues superfluous.

According to this invention the two pairs of regenerators are connected to the outer ends of two horizontal superposed canals, each extending across the whole width of the battery and below all the flues of a heating wall, equal length of the gas travel being obtained by arranging the two canals to cross each other in the middle so that one half of each canal extends below, the other half above the other canal.

In the drawings affixed to this specification and forming part thereof two modifications of a coke oven battery embodying my invention are illustrated diagrammatically by way of example.

Fig. 1 is a vertical cross section of the battery on the line C—C in Fig. 2.

Figs. 2 and 3 are vertical longitudinal sections on the lines A—A and B—B, respectively, in Fig. 1, and

Fig. 4 is a horizontal section on the line E—E in Fig. 1, the oven here shown being of the type in which the heating flues in each heating wall are arranged in pairs, the flues in each pair being traversed by the gases in opposite direction.

Fig. 5 is a vertical cross section of the battery on the line B—B in Fig. 6,

Fig. 6 is a vertical longitudinal section on the line A—A in Fig. 5, and

Fig. 7 is a horizontal section on the line D—D in Fig. 5, the oven here shown being of the type, in which pairs of adjoining heating walls are connected on top by conduits extending across the coking chamber enclosed between them, the gases entering at the foot of one heating wall and after having traversed same upwardly pass through the said conduit into the top part of the other heating wall of the pair, traversing same downwardly.

Referring first to Figs. 1-4, 10 are the coking chambers and 11 are the heating walls each comprising a row of pairs of vertical flues *a* and *b*, each pair being separated by a vertical partition 19 and communicating with each other by a passage 20. The oven here shown being designed to be operated with a change of direction of the flow of the gases in predetermined intervals, these pairs of heating flues are supplied in the first time interval with gas and air entering through separate ducts 7*a*, 7*b* in the bottom of the flues *a*, the waste gases formed by the combustion of the mixture of gas and air flowing downwardly through the corresponding flues *b* and escaping through ducts 8*a*, 8*b*. After reversal of the valves provided for this purpose the gas and air as well as the waste gases will travel in the opposite direction. The coal charged into the coking chambers is then heated and converted into coke, the gases formed being drawn off in a manner well known to a person skilled in the art.

Underneath the oven structure formed by the alternating heating walls 11 and coking chambers 10 and at right angles thereto the regenerators 12, 13, 14, 15 extend in parallel throughout the length of the battery of ovens, each being filled with checker work. These regenerators are arranged to cooperate in pairs. Whenever the regenerators 14 and 15 are utilized for preheating air and poor gas, respectively, the regenerators 12 and 13 are traversed in the same time interval by the waste heat, while in the interval next following, when the valves have been reversed, the

regenerators 12 and 13 serve for preheating.

As shown by the arrows in Fig. 1, air is led into regenerator 14 to be preheated to about 1000° C. in contact with the hot checker work 5 and to escape through a conduit 2 into the outer end of a horizontal canal 16a extending below and across the entire length of a row 11 of heating flues *a* and *b*, the first half of this canal being arranged in a lower, the second half in an upper plane, a slightly ascending conduit 5a connecting the inner ends of the two halves. The hot air flows from the canal 16a through ducts 7a into the flues *a*. In a similar manner gas preheated in regenerator 15 flows through a conduit 4 to the outer end of canal 16b which extends in parallel to the canal 16a and the two halves of which are also disposed in different planes, being connected by a slightly ascending conduit 5b (Fig. 4).

Ducts 7b lead from canal 16b to the heating flues *a* and the preheated gas escaping from these ducts will mix in the flues *a* with the preheated air entering through the ducts 7a, as described above, the mixture being burnt and the flame and waste gases flowing through the passages 20 and downwardly through the adjoining flues *b*, escape through ducts 8a and 8b at the bottom ends of these flues into two canals 17a and 17b, respectively, which lead to the regenerators 12 and 13, respectively. Canal 17a has one half extending above that half of canal 16a, which was supplied with the air preheated in regenerator 14, and another half extending below the second half of canal 16a, as shown in Fig. 1, and connected with regenerator 12 by a conduit 1. The two halves of canal 17a are connected by a slightly descending conduit 6a (Fig. 4) which crosses the conduit 5a, without, however, intersecting it, being separated from it by a wall 40 which being disposed in the middle of the oven structure is not exposed to any appreciable expansion and contraction and is therefore not liable to crack. In a similar manner canal 17b extends partly above and partly below the two halves of canal 16b, its connecting conduit 6b crossing conduit 5b, which connects the two halves of canal 16b, being separated therefrom by a wall 41.

As best shown in Fig. 2, each canal 16a or 16b supplies preheated air or gas simultaneously to the flues *a* of two adjoining heating walls 11, the waste gases escaping from the flues *b* into the canals 17a and 17b, respectively.

Obviously, when after a predetermined interval of time the valves have been reversed, air and gas will be preheated in the regenerators 12 and 13, respectively, in which was stored the heat of the waste gases formed in the preceding operation, and will travel through canals 17a and 17b, respectively, through flues *b* and *a* of adjoining heating

walls, down into canals 16a and 16b and out through regenerators 14 and 15, respectively.

In the oven illustrated in Figs. 5-7 the arrangement of superposed and intercrossing canals is similar to the one provided in the construction described with reference to Figs. 1-4. However, the way of the gases differs in that the heating walls cooperate in pairs in a well known manner, each heating wall being formed of a row of uniform flues and pairs of adjoining heating walls being arranged for cooperation by connecting their flues by means of conduits extending across the coking chamber flanked on both sides by the heating walls in question. If these heating walls are operated in such manner that those heating walls of two adjoining pairs, which enclose a coking chamber between them, are traversed by the gases in the same direction, the arrangement of distributing canals described with reference to Figs. 1-4 can be simplified by replacing alternating superposed and intercrossed canals by a single canal, as will be described more particularly with reference to Figs. 5-7.

Here pairs of adjoining heating walls 33 and 34 enclose between them coking chambers 35, the heating walls of each pair being connected with each other across such coking chamber by passages 36, one for each flue, horizontal channels 37 common to all the flues of a heating wall and a number of U-shaped conduits 38 connecting the channels 37 of each pair. Underneath this oven structure are arranged four regenerators 50, 51, 52, 53, filled with checkerwork and extending in parallel across the entire length of the oven battery and at right angles to the heating walls and coking chambers. The two outer regenerators 50, 53 are connected by means of conduits 21, 22, respectively, with two canals 27 and 26, respectively, one half of canal 26 being superposed to one half of canal 27, and vice versa, and the halves of each canal being connected with each other by a sloping conduit 25 and 29, respectively, these conduits crossing each other, without intersecting, as shown in Fig. 7. Such superposed canals are arranged below those coking chambers which are enclosed between communicating heating walls. Underneath each of the other coking chambers is disposed a simple canal marked 39 and 59, respectively, the canals 39 being connected by means of conduits 24 with regenerator 52, the canals 59 by means of conduits 23 with regenerator 51. The canals 26 and 27 communicate with the flues 34 and 33 by means of ducts 30 and 31, respectively, canals 58 and 59 each with the flues 33 of one and flues 34 of an adjoining pair of heating walls by means of ducts 68 and 69, respectively.

Supposing air to be supplied to regenerator 53 to be preheated therein, the hot air will flow through conduit 22, canal 26 and

duets 30 upwardly in the heating walls 34. At the same time gas supplied to and pre-heated in regenerator 52 will flow through conduit 24, canal 58 and ducts 68 to mix with the hot air supplied to the heating walls 34. The flame of combustion will rise in these heating walls and the hot gases of combustion will pass through passages 36, channels 37 and conduits 38 into the heating walls 33, descending therein and part thereof escaping through ducts 31 into canals 27 and through conduits 21 into regenerator 50, while another part will escape through ducts 69 into canals 59 and out through conduits 23 into regenerator 51, whereby these regenerators are heated up. After reversal of the valves air and gas will enter through the regenerators 50, 51, respectively, will flow through canals 27 and 59 and rise in the heating walls 33, the waste gases will descend through heating walls 34 and will escape through ducts 30, canals 26, conduits 22 and regenerator 53 on the one hand, and through ducts 68, canals 58, conduits 24 and regenerator 52.

Openings 65 in the outer walls of the ovens communicating with the outer ends of the canals allow subsequently providing for the gas-tight sealing of the walls separating adjoining canals.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. A coke oven battery comprising, a series of alternate horizontal coking chambers and heating walls therefor arranged laterally of each other in a row, each of said heating walls comprising a row of combustion flues; regenerators extending longitudinally of the battery and substantially at right angles to said coking chambers and said heating walls; a pair of canals extending in a generally horizontal direction below each of said coking chambers parallel therewith and above said regenerators, each of the canals being formed in two substantially horizontal portions arranged at different levels with a sloping conduit connecting the said portions, the sloping conduits of the canals of a pair crossing each other and a wall separating them, each of the canals of a pair communicating with some of the combustion flues of one of said heating walls and the lower horizontal portion of each of the canals communicating with one of the regenerators below such portion.

with one of the regenerators below such portion.

2. A coke oven battery comprising, a series of alternate horizontal coking chambers and heating walls therefor arranged laterally of each other in a row, each of said heating walls comprising a row of combustion flues; regenerators extending longitudinally of the battery and substantially at right angles to said coking chambers and said heating walls; a pair of canals extending in a generally horizontal direction below each of said coking chambers parallel therewith and above said regenerators, each of the canals being formed in two substantially horizontal portions arranged at different levels with a sloping conduit connecting the said portions, the canals within each of the pairs extending substantially in one vertical plane with their horizontal portions alternately superposed and the sloping conduits crossed; and a wall separating said crossed conduits; each of the canals of a pair communicating with some of the combustion flues of one of said heating walls and the lower horizontal portions of each of the canals communicating with one of the regenerators below such portion.

3. A coke oven battery comprising, a series of alternate horizontal coking chambers and heating walls therefor arranged laterally of each other in a row, each of said heating walls comprising a row of combustion flues; regenerators below said coking chambers and said heating walls; a pair of canals extending in a generally horizontal direction below each of said coking chambers parallel therewith and above said regenerators, each of the canals being formed in two substantially horizontal portions arranged at different levels with a sloping conduit connecting the said portions, the sloping conduits of the canals of a pair crossing each other and a wall separating them; each of the canals of a pair communicating with some of the combustion flues of one of said heating walls and the lower horizontal portion of each of the canals communicating with one of the regenerators below such portion.

4. A coke oven battery comprising, in combination: a series of alternate horizontal coking chambers and heating walls therefor arranged laterally of each other in a row, each of said heating walls comprising a row of combustion flues; regenerators below said coking chambers and said heating walls; a pair of canals extending in a generally horizontal direction below each of said coking chambers parallel therewith and above said regenerators, each of the canals being formed in two substantially horizontal portions arranged at different levels with a sloping conduit connecting the same portions, the canals of the pairs extending substantially in one vertical plane with their

horizontal portions alternately superposed and the sloping conduits crossed; and a wall separating said crossed conduits; each of the canals of a pair communicating with some of the combustion flues of one of said heating walls and the lower horizontal portions of each of the canals communicating with one of the regenerators below such portion.

5. A coking retort oven battery comprising, in combination: a series of alternate horizontal coking chambers and heating walls therefor arranged laterally of each other in a row, each of said heating walls comprising vertical combustion flues; regenerators arranged in two sets disposed side by side transversely of the battery below said coking chambers and said heating walls, one of said sets of regenerators being operable for inflow of combustion media while the other of said sets of regenerators operates simultaneously for outflow of waste gas and reversely; and a pair of canals extending in a generally horizontal direction below each of some of said coking chambers parallel therewith and above both of said two sets of regenerators, each of the canals being formed in two substantially horizontal portions arranged at different levels with one of the portions of each of the canals over one of the sets of regenerators and the other portion of each of the canals over the other set of regenerators and with the portion of each canal over one set of regenerators of the same length and elevation as the portion of the other canal over the other of the sets of regenerators; each of the canals of a pair communicating with some of the combustion flues above both of the two sets of regenerators and the portions of each of the canals that are of the same elevation communicating with one of the regenerators below such portions.

6. A coking retort oven battery comprising, in combination: a series of alternate horizontal coking chambers and heating walls therefor arranged laterally of each other in a row, each of said heating walls comprising vertical combustion flues; regenerators arranged in two sets disposed side-by-side transversely of the battery below said coking chambers and said heating walls, one of said sets of regenerators being operable for inflow of combustion media while the other of said sets of regenerators operates simultaneously for outflow of waste gas and reversely; and a pair of canals extending in a generally horizontal direction below each of some of said coking chambers parallel therewith and above both of said two sets of regenerators, each of the canals being formed in two substantially horizontal portions arranged at different levels with one of the portions of each of the canals over one of the sets of regenerators and the other portion of each of the canals over the other set of re-

generators, the canals of the pairs extending substantially in one vertical plane with their horizontal portions alternately superposed and with the portion of each canal over one set of regenerators of the same length and elevation as the portion of the other canal over the other of the sets of regenerators; each of the canals of a pair communicating with some of the combustion flues above both of the two sets of regenerators and the portions of each of the canals that are of the same elevation communicating with one of the regenerators below such portions.

7. A coke oven battery comprising: a series of alternate horizontal coking chambers and heating walls therefor arranged laterally of each other in a row, each of said heating walls comprising vertical combustion flues; two pairs of longitudinal regenerators operable in alternation with each other and extending longitudinally of the battery transversely of the coking chambers, said two pairs of regenerators being disposed below the coking chambers and heating walls on opposite sides of the battery respectively; means communicably connecting the tops of each of the vertical flues of each of said heating walls with the tops of others of the vertical heating flues of said walls so as to provide two sets of vertical flues operable for concurrent inflow combustion and outflow of waste gas in alternation with each other above both of said two pairs of regenerators; a pair of superposed canals, extending in a generally horizontal direction below each of some of said coking chambers parallel therewith and above both of said two pairs of regenerators; and other canals extending in a generally horizontal direction below each of the other of said coking chambers parallel therewith and above both of said two pairs of regenerators; one of the canals of each of the pairs thereof communicating with some of the flues of one of the two sets thereof above both pairs of regenerators and being communicably connected at the end thereof above one of said pairs of regenerators to one of the regenerators of each of the pairs of canals communicating with some of the flues of the other of the two sets of flues above both pairs of regenerators and being communicably connected at the end thereof above the other pair of regenerators to one of the regenerators thereof; some of the said other canals below the others of said coking chambers communicating with some of the flues above both pairs of regenerators of said one of the two sets of flues and being communicably connected at the end thereof above said one of said pairs of regenerators to the other of the regenerators thereof, and the remainder of said other canals last aforesaid communicating with some of the flues above both pairs of regenerators of said the other of the

two sets of flues and being communicably connected at the end thereof above said the other pair of regenerators to the other of the regenerators thereof.

5. 8. A coke oven battery comprising: a series of alternate horizontal coking chambers and heating walls therefor arranged laterally of each other in a row, each of said heating walls comprising vertical combustion flues; two pairs of longitudinal regenerators operable in alternation with each other and extending longitudinally of the battery transversely of the coking chambers, said two pairs of regenerators being disposed below the coking chambers and heating walls on opposite sides of the battery respectively; a pair of superposed canals, extending in a generally horizontal direction below each of some of said coking chambers parallel therewith and above both of said two pairs of regenerators; and other canals extending in a generally horizontal direction below each of the others of said coking chambers parallel therewith and above both of said two pairs of regenerators; one of the canals of each of the pairs thereof communicating with the vertical flues that are above both pairs of regenerators and that are in one of the heating walls of a cross-connected pair thereof and being communicably connected at the end thereof above one of said pairs of regenerators to one of the regenerators thereof; and the other of the canals of each of the pairs of canals communicating with vertical flues that are above both pairs of regenerators and that are in the other of the heating walls of a cross-connected pair and being communicably connected at the end thereof above the other pair of regenerators to one of the regenerators thereof; some of said other canals below the others of said coking chambers communicating with the vertical flues that are above both pairs of regenerators in each of two of the said one of said heating walls of a cross-connected pair and being communicably connected at the end thereof above said one of said pairs of regenerators to the other of the regenerators thereof, and the remainder of said other canals last aforesaid communicating with vertical flues that are above both pairs of regenerators in each of two of the said the other of the heating walls of a cross-connected pair and being communicably connected at the end thereof above said the other pair of regenerators to the other of the regenerators thereof.

9. A coke oven battery comprising: a series of alternate horizontal coking chambers and heating walls therefor arranged laterally of each other in a row, each of said heating walls comprising a row of vertical combustion flues, said heating walls being operatively connected in pairs by having the vertical

flues in each of said heating walls communicably connected with vertical flues in another of said heating walls by cross-over conduits crossing over the intervening coking chambers; two pairs of longitudinal regenerators operable in alternation with each other and extending longitudinally of the battery transversely of the coking chambers, said two pairs of regenerators being disposed below the coking chambers and heating walls on

70 opposite sides of the battery respectively; a pair of superposed canals, extending in a generally horizontal direction below each of some of said coking chambers parallel therewith and above both of said two pairs of regenerators; and other canals extending in a generally horizontal direction below each of the others of said coking chambers parallel therewith and above both of said two pairs of regenerators; one of the canals of

75 each of the pairs thereof communicating with the vertical flues that are above both pairs of regenerators and that are in one of the heating walls of a cross-connected pair thereof and being communicably connected at the end thereof above one of said pairs of regenerators to one of the regenerators thereof; and the other of the canals of each of the pairs of canals communicating with vertical

80 flues that are above both pairs of regenerators and that are in the other of the heating walls of a cross-connected pair and being communicably connected at the end thereof above the other pair of regenerators to one of the regenerators thereof; some of said other canals below the others of said coking chambers communicating with the vertical

85 flues that are above both pairs of regenerators and that are in the other of the heating walls of a cross-connected pair and being communicably connected at the end thereof above said one of said pairs of regenerators to the other of the regenerators thereof, and the remainder of said other canals last aforesaid communicating with vertical flues that are above both pairs of regenerators in each of two of the said the other of the heating walls of a cross-connected pair and being communicably connected at the end thereof above said the other pair of regenerators to the other of the regenerators thereof.

90 10. A coke oven battery comprising: a series of alternate horizontal coking chambers and heating walls therefor arranged laterally of each other in a row, each of said heating walls comprising a row of inverted U-shaped vertical combustion flues operable for concurrent inflow combustion and outflow of waste gas in alternation with each other; two pairs of longitudinal regenerators operable in alternation with each other and extending longitudinally of the battery transversely of the coking chambers, said two pairs of regenerators being disposed below the coking chambers and heating walls and on
